UNITED STATES PATENT OFFICE.

GEORGE B. BURRAGE, OF CHICAGO, ILLINOIS.

FILING-CASE.

No. 831,024.

Specification of Letters Patent.

Patented Sept. 11, 1906.

Application filed March 16, 1906. Serial No. 306,154.

To all whom it may concern:

Be it known that I, GEORGE B. BURRAGE, a citizen of the United States, residing at 156 Wabash avenue, Chicago, in the county of Cook and State of Illinois, have invented a new and useful Improvement in Filing-Cases, of which the following is a specification.

My invention relates to cases or drawers adapted to hold cards, slips, or files in position to permit ready access to and inspection of any part of the contents of the case.

My primary object is to provide improved adjusting means for the follower or movable backer of a filing-case or drawer of the nature indicated.

The invention is illustrated in its preferred embodiment in the accompanying drawings, in which—

20 Figure 1 represents a perspective view of a filing case or drawer embodying my invention; Fig. 2, a transverse section taken as indicated at line 2 of Fig. 1; Fig. 3, a broken bottom plan view of the case; Fig. 4, a 25 broken vertical section through the follower and its guide, taken as indicated at line 4 of Figs. 2 and 3; Fig. 5, a broken central vertical section taken as indicated at line 5 of Fig. 3, and Fig. 6 a broken end elevational view 30 showing a detail of the connection between the follower-guide and the end of the drawer.

In the preferred construction, the device comprises a casing or drawer A, having a central longitudinal slot or channel a in its bottom a' , a follower-guide A' , comprising a metallic strip located in said slot and having its ends joined by screws a^2 to the lower edges of the ends a^3 a^4 of the drawer, as shown in detail in Fig. 6, and a follower or backer A^2 , 40 equipped with a metal guide member a^5 , movable on the guide A' .

The front end a^3 of the drawer is provided with the usual inclined rest a^6 for the cards to bear against, and the follower A^2 has an opposed inclined surface a^7 . The follower may comprise a wooden block freely movable between the sides of the drawer. The guide member A' has its metal struck downwardly at points a^8 to afford a series of locking-shoulders a^9 , the metal being preferably severed at the sides and rear end of each struck-down portion, leaving a series of rearwardly-declining tongues a^{10} . The guide member a^5 , with which the follower is equipped on the 50 central portion of its lower surface, may be formed of sheet metal. It has at its front

portion a pair of downwardly-projecting in-turned lugs a^{11} , which embrace the guide member A' , it being observed that the spaces between the lateral edges of the member A' 60 and the adjacent lateral walls of the slot a are sufficient to permit passage of the lugs, and the member a^5 is further equipped near its rear end with downwardly-extending in-turned lugs a^{12} , which embrace the member A' , 65 one of the lugs a^{12} bearing a forwardly-extending spring a^{13} , whose free end is slightly curved and bears on the under surface of the member A' adjacent to the row of depressions therein. At the rear portion of the slide a^5 70 is a rearwardly-declining lug or tooth a^{14} , adapted to engage the shoulders a^{14} of the member A' . The lugs a^{11} of the slide a^5 have but little clearance beneath the member A' , and the lugs a^{12} have considerable clearance, 75 the slide being normally held in the horizontal position shown in Fig. 4 by the spring a^{13} . It will now be understood that the follower may be moved freely toward the front end of the drawer, the tooth a^{14} riding freely over 80 the rack of the member A' and the spring a^{13} yielding to permit this action. Moreover, the follower will be automatically locked against retrograde movement at all times. When desired, however, the follower may be 85 tilted forcibly forward to keep the catch a^{14} free from the rack, leaving the follower free to be retracted, as desired.

The construction is simple, cheap, and durable and perfectly adapted to its purpose. 90

What I regard as new, and desire to secure by Letters Patent, is—

1. The combination with a case or drawer, of a guide member extending longitudinally at the bottom thereof and provided with a series of locking-shoulders engageable from above, a follower equipped with a slide movable on said guide member, said slide being tiltable with relation to the guide member and having a tooth movable over the upper 100 surface of the guide member, and a spring carried by said slide and bearing beneath the guide member, for the purpose set forth.

2. The combination with a drawer, of a longitudinally-extending metallic strip at the bottom thereof formed with a series of locking-shoulders, a follower movable longitudinally in the drawer and equipped with a slide, said slide having depending in-turned lugs embracing said strip, the rear lugs being 110 spaced to permit forward tilting of the follower, a spring connected with the slide and

bearing on the under surface of said strip and serving normally to maintain the slide in a horizontal position, and a locking-shoulder carried by the rear portion of the slide and 5 adapted to move over the upper surface of said strip.

3. The combination of a case or drawer having a longitudinal slot in its bottom, a guide member located in said slot and 10 equipped with a series of locking-shoulders, spaces being allowed between the lateral edges of said guide member and adjacent lateral walls of the slot, a follower equipped 15 with a slide having a depending pair of in-turned lugs at its front portion embracing said guide member and a depending pair of lugs at its rear portion embracing said guide member loosely to permit tilting, a spring projecting forwardly from one of said lugs and 20 bearing upon the under surface of said guide member, and a lug projecting from the rear portion of said slide and adapted to engage the locking-shoulders of said guide member.

4. The combination with a drawer having

a longitudinal slot in its bottom, of a metallic 25 guide member located in said slot and having a series of struck-down portions affording rearwardly-declining tongues and locking-shoulders adjacent thereto, a follower, and a slide connected with the base of said follower comprising a sheet-metal member having a 30 pair of front depending inturned lugs embracing said guide member somewhat closely and a pair of rear depending lugs embracing said guide member more loosely, a forwardly-extending spring carried by one of the rear lugs and having its free end bearing on the 35 lower surface of said guide member, and a rearwardly-declining lug carried by the rear portion of the slide and moving over the upper surface of said guide member and adapted 40 to engage the locking-shoulders thereof, substantially as and for the purpose set forth.

GEORGE B. BURRAGE.

In presence of—

GEORGE A. CHRITTON,
Wm. H. THOMPSON.
